UNITED STATES PATENT OFFICE.

LESLIE COMBS BUNNELL, OF PARIS, KENTUCKY.

PAPER-BAG HOLDER.

SPECIFICATION forming part of Letters Patent No. 721,996, dated March 3, 1903.

Application filed December 30, 1902. Serial No. 137,163. (No model.)

To all whom it may concern:

Be it known that I, LESLIE COMBS BUNNELL, a citizen of the United States, and a resident of Paris, in the county of Bourbon and State of Kentucky, have invented a new and Improved Paper-Bag Holder, of which the following is a full, clear, and exact description.

This invention relates to means for holding paper bags in quantity lapped and clamped together in sequence, ready for removal singly or in greater number, as may be required, and has for its object to provide novel details of construction for a device of the character indicated which adapt the novel bag-holder for very efficient service and enable the instant removal of one or more bags without disarranging others left remaining in the holder.

The invention consists in the novel construction and combination of parts, as is hereinafter described, and defined in the appended claims.

Reference is to be had to the accompanying drawings, forming a part of this specification, in which similar characters of reference indicate corresponding parts in all the figures.

Figure 1 is a perspective view of the improved bag-holder shown holding a number of paper bags. Fig. 2 is a rear view of the device, and Fig. 3 is a transverse sectional view of the improvement substantially on the line 3-3 in Fig. 1.

In the drawings that represent the construction and application of the novel bag-holder, 5 indicates the back board, whereon the paper bags A are removably clamped. As shown, the back board 5 consists of a preferably wooden planchette rectangular in form and having dimensions proportioned to the size of the paper bags said back board is to support. At a suitable point near one end of the back board 5 a transverse groove a is formed in its rear surface at right angles to the parallel side edges of the board. From the transverse groove a two spaced short grooves a' extend, these being respectively near the side edges of the board 5, the grooves a' having equal depth to that of the groove a, of which they virtually are portions, and project from the same side edge of the transverse groove.

A holder-clamp, preferably formed of a sin-

gle resilient wire strand, is provided to retain the paper bags compressed upon the front of the back board 5 and is constructed as follows: At a proper distance from each end of the wire material a right-angle bend b is formed in said wire strand, thus providing a clamping-bar 6 and two parallel members 6^a, that are side arms of the holder-clamp. The length of the clamping-bar 6 is proportioned to the width of the back board 5 and should slightly exceed it, so that the arms 6^a may loosely embrace the side edges of the back board. At two points b' equally distant from the bends b the wire material is again bent, so as to project two members 6^b of equal length toward each other and parallel with the clamping-bar 6. At a short distance from the free ends of each of the holder members 6^b a finger 6^c is formed by bending the material at a right angle, as indicated at c in Fig. 2. The length of the members 6^b is equal and so proportioned that the fingers 6^c may be bedded in the lateral grooves a' when the said members 6^b are seated in the transverse groove a near and substantially parallel with each other, and, as shown in Fig. 2, the holder members 6^b are secured upon the back board 5 by a plurality of staples 7, that are caused to embrace said members and are firmly affixed in the back board, as indicated in Fig. 3.

It will be seen that the provision of the fingers 6^c on the members 6^b converts said portions of the holder-clamp into tension-springs, which coact with the arms 6^a and transverse bar 6 to afford a spring-clamp. As indicated for one arm 6^b in Fig. 1, said arms are kinked, as at d, near the angular bends b', which causes the clamping-bar 6 to press with greater force upon a small number of paper bags than it otherwise would.

An important detail of the invention embodies simple and efficient means for clamping a plurality of paper bags A at their side edges A' when they are held in position on the back board 5 by the clamping-bar 6, said means comprising a novel supplementary clamp that will be described.

A resilient wire strand is provided of suitable length and bent into a loop e at the center of its length, which loop is secured upon the rear of the back board 5 at its transverse

center above the groove *a* therein by a staple *e*. The back board 5 is oppositely notched in its side edges, preferably near the clamping-bar 6, said notches *g* having a depth that 5 adapts them to underlie the side edges of the bags A when clamped on the back board. A bend *h* is formed at a proper distance from each extremity of the wire material, thus producing two pressure-limbs 8^a on the divergent arms 8, that extend from the loop *e* outward and downward to the notches *g*, in which the pressure-limbs 8^a are positioned and project forwardly. The main arms 8 are secured upon the rear surface of the back board 5 at suitable points by staples *e*², and it is essential that these staples be positioned far enough from the pressure-limbs 8^a to permit the latter to exert torsional stress laterally or upon the side edges A' of the paper bags A when the latter are clamped upon the back board 5. The length of the pressure-limbs 8^a should be sufficient to permit them to have contact with a considerable number of paper bags A when they are clamped upon the back board 5, and it will be seen that within a proper range the bag-holder complete will receive and hold bags of more than one width and capacity.

In service, assuming that the back board 5 is supported in any preferred manner and by any suitable means at a point for the convenient delivery of paper bags and that a sufficient number of the latter are held on said back board by the joint action of the clamping-bar 6 and the resilient limbs 8^a, it will be seen that by pulling upon the lower end of a bag A it will slip from the clasp of the bar 6 and limbs 8^a, as may be required. Furthermore, as the pressure-limbs 8^a frictionally engage the side edges of the paper bags such as are not subjected to a direct pull will remain clamped upon the back board 5. Obviously by taking hold of two or more bags at a time these may be together pulled 45 from the bag-holder.

As each size of the improved bag-holder will accommodate two or three widths of paper bags, it will be seen that few sizes need be provided to properly hold all the paper bags used, from the largest to the smallest of such paper receptacles.

Having thus described my invention, I claim as new and desire to secure by Letters Patent—

55 1. A paper-bag holder comprising a back board, a holder-clamp that presses a plurality of paper bags against the back board, and a supplementary clamp having two spring-

pressed limbs which have enforced contact with the side edges of the clamped paper bags. 60

2. A paper-bag holder comprising a back board, a holder-clamp comprising two spring-pressed arms, and a transverse bar which engages the outer one of a series of paper bags imposed on the back board, and a supplementary clamp consisting of two spring-pressed limbs which have enforced contact with the side edges of paper bags clamped upon the back board. 65

3. A paper-bag holder comprising an oblong back board, a holder-clamp formed of resilient wire, having a clamping-bar, two side arms on the ends of the clamping-bar, two members on the ends of the side arms spaced from and parallel with the clamping-bar, a finger bent on each of said members, means for securing the holder members on the rear face of the back board, and a supplementary clamp comprising two spring-arms bent at the ends thereof to form integral pressure-limbs thereon, and means for securing the spring-arms on the rear face of the back board, so as to dispose the pressure-limbs at the side edges of the back board and adapt them to press upon the side edges of 85 paper bags clamped on the back board.

4. A paper-bag holder, comprising an oblong rectangular back board having a transverse groove in its rear face, and two grooved extensions intersecting the transverse groove 90 at one edge near the ends thereof, of a holder-clamp comprising a transverse clamping-bar, two integral resilient arms extended at right angles from the ends of the clamping-bar, two spring members formed at the ends of the resilient arms parallel with the clamping-bar, a lateral finger bent on the free end of each spring member, said members and fingers being secured in the grooves of the back board so as to give torsional force to the spring-arms, and a supplementary spring-clamp comprising two integral spring members bent from a wire rod diverging from a loop thereon, means for securing said members on the rear face of the back board, and a pressure-limb formed on the free end of each spring member, each limb extending forwardly through a notch formed in a respective side edge of the back board. 100 105

In testimony whereof I have signed my name to this specification in the presence of two subscribing witnesses.

LESLIE COMBS BUNNELL.
